UNITED STATES PATENT OFFICE.

LEOPOLD J. LINKIEWICZ, OF BROOKLYN, NEW YORK.

VENDING-MACHINE.

1,237,919.

Specification of Letters Patent.

Patented Aug. 21, 1917.

Application filed February 5, 1917. Serial No. 146,613.

To all whom it may concern:

Be it known that I, LEOPOLD J. LINKIEWICZ, a citizen of the United States, and a resident of the city of New York, borough 5 of Brooklyn, in the county of Kings and State of New York, have invented a new and Improved Vending-Machine, of which the following is a full, clear, and exact description.

10 This invention relates to vending machines and has for an object the provision of an improved construction for vending small articles successively from a container.

Another object in view is to provide a 15 construction for vending articles from a container or hopper in which only one can be discharged on each operation of the machine.

A still further object of the invention is 20 to provide in a vending machine an improved arrangement of coin actuated mechanism and automatic resetting means therefor.

In the accompanying drawing:

Figure 1 is a sectional view through Fig. 2 25 on line 1—1.

Fig. 2 is a sectional view through Fig. 1 on line 2—2.

Fig. 3 is a longitudinal horizontal section through Fig. 1 on line 3—3.

30 Fig. 4 is a transverse section through Fig. 2 on line 4—4.

Referring to the accompanying drawings by numerals, 1 indicates a base to which a casing 2 is secured in any suitable way, as 35 for instance, by bolts or rivets. The casing 2 is provided with a hopper 3 at the upper end having a lid 4 held in place by a pin 5, said pin being locked against removal by any suitable lock 6. This arrangement of 40 pin and lock is provided in order that the hopper 3 may be refilled easily at any time without disturbing the mechanism in casing 2. Arranged in the casing 2 is a drum 7 provided with a plurality of plates or blades 45 8 forming compartments 9 into which the articles 10 pass, as shown in Fig. 4, when being distributed. These articles may be any desired commercial article, which are formed in packages capable of being easily 50 fed into the compartments 9 and being discharged in such manner as to pass out through the chute 11 to the delivery cup 12. A resilient stop 13 is connected to shaft 14, said stop engaging the blades 8 as shown in 55 Fig. 4 for preventing the reverse movement while resiliently allowing a forward move-

ment. An arm 15 is also connected with shaft 14, said arm bearing against the plate 16 so as to prevent the reverse rotary movement of shaft 14 while allowing a forward 60 movement if desired.

As shown in Figs. 2 and 3, the drum 7 is arranged in the room 17, while an auxiliary room 18 is provided at one side for receiving the ratchet wheel 19 and the coin receiving 65 and operating mechanism. Said coin receiving and operating mechanism is provided with a wheel 20 having a coin slot 21 and a groove 22, said groove being of any suitable length, as for instance, a half circle as shown 70 in Fig. 1. A pin 23 is secured to a division wall 24 and extends into slot 22 so as to limit the back and forth rocking movement of the wheel 20. A shaft 25 is rigidly secured to wheel 20, said shaft being journaled in the 75 division wall 24 and in a boxing 26 (Fig. 2), said boxing containing a spring 27 connected at one end to shaft 25 and at the opposite end to casing 2. This spring gives shaft 25 and parts connected therewith a 80 continuous tendency to move back to the position shown in Fig. 1 and to remain in said position. An operating handle 28 in the form of a wheel is connected to shaft 25 so as to rotate the same when the machine is being 85 operated.

In order to operate the machine and secure one of the packages or articles 10, a coin of the proper size is deposited in the coin guide 29 and said coin will move downwardly by 90 gravity until it reaches the bottom of the coin slot 21 in wheel 20. The guide 29 is cut away at 30 so that the coin may freely move in the direction indicated by the arrow in Fig. 1 until it strikes one of the teeth 95 of the ratchet wheel 19 and moves said ratchet wheel for a distance of one tooth or one compartment 9, whereupon the lowermost package or article 10 will be moved away from the retaining housing 31 (Fig. 4) 100 and allowed to drop on to the inclined chute 11, whereupon the same will move by gravity to the delivery cup 12. The spring member 13 will prevent a reverse rotation of the drum 7 and will resist resiliently a forward 105 motion so that the drum is properly held in position until positively moved by a rotation of the sprocket wheel 19, which sprocket wheel is rigidly secured to the shaft 32, which shaft in turn is rigidly secured to the 110 drum 7.

After the handle 28 has been rotated as

far as possible, as for instance, a half-revolution, the coin will drop out of the slot 21, as shown in Fig. 1, and then the wheel 20 and parts connected therewith will return to their first position ready to receive a second coin. It will be noted that the second coin cannot be used until the first coin has been disposed of, as there is only one coin slot in the wheel 20. Arranged at the bottom 10 of the auxiliary room 18 is a coin tray 33, which may be provided with a suitable lock or securing means for holding the same against unauthorized removal.

What I claim is:

15 In a vending machine of the character described, a vending drum, a ratchet wheel,

rigidly secured to said drum, a coin wheel arranged adjacent said ratchet wheel and in substantially the same plane, said coin wheel being provided with an arc-shaped groove in 20 one side and a coin slot in the edge of less depth than the diameter of the coin to be used whereby when a coin is used in said slot and the coin wheel is rotated the coin therein will engage said ratchet wheel and move 25 the same to a predetermined distance, a pin extending into said groove for limiting the radial movement of said wheel in both directions, and means for directing a coin to said slot.

LEOPOLD J. LINKIEWICZ.
